UNITED STATES PATENT OFFICE.

ULYSES S. GEIGER, OF NORTH ENGLISH, IOWA

STARTING DEVICE.

Application filed August 16, 1926. Serial No. 129,446.

The present invention relates to improvements in starting devices for automobiles. One of the important objects of the present invention is to provide a starting device for internal combustion engines which includes a simplified drive mechanism for one of the rotating parts of the engine such as for example the fly wheel.

Another important object of the invention is to provide a starting device of the above mentioned character which includes an axially movable driven shaft on which is keyed a driving gear or pinion which is adapted for cooperation with the gear teeth of the fly wheel of an internal combustion engine, means being provided for yieldably limiting the axial movement of the shaft.

A further object is to provide a starting device of the above mentioned character which will at all times be positive and efficient in its operation, the same being further simple in construction, inexpensive, strong and durable, and further well adapted to the purpose for which it is designed.

Other objects and advantages of the invention will become apparent from the following description taken in connection with in the accompanying drawing.

In the accompanying drawing forming part of this application and in which like reference characters indicate like parts:

The figure represents a side elevation, partly in section of the starting device embodying my invention.

In the drawing wherein for the purpose of illustration is shown the preferred embodiment of my invention, the numeral 1 designates the drive shaft which extends from any suitable prime mover such as for example a starting motor, not shown. Secured on the outer end of this shaft and adapted for rotation therewith is the driving pinion or gear 2.

Disposed parallel with the drive shaft 1 is the driven shaft 3. This shaft extends through suitable registering openings provided therefor in a supporting frame or casing designated generally by the numeral 4 and suitable bushings 5 and 6 are disposed in the respective openings of the supporting frame or casing in the manner as clearly shown in the drawing. The inner end of the driven shaft 3 is reduced as at 7 and the outer end of the reduced portion 7 extends through a suitable opening provided therefor in a cover plate 8 which is secured

to the outer face of the inner side portion of the supporting frame or casing 4 by the appropriate fastening means as at 9 for retaining the bushing 6 in position against accidental displacement. This driven shaft is further adapted for axial movement in the manner to be hereinafter more fully described.

A driving gear or pinion 10 is adjustably secured on the outer end of the driven shaft 3 by means of the collar 11 and the set screw 12. This driving gear or pinion 10 is further adapted for rotation simultaneously with the driven shaft 3 and is further adapted for cooperation with the gear teeth 13 which are cut in the peripheral edge of the fly wheel 14 which forms a part of an internal combustion engine and which element is to be actuated by the starting mechanism.

Keyed on the intermediate portion of the driven shaft 3 is the relatively wide spiral gear 15, the same being adapted for axial movement simultaneous with the driven shaft 3.

An expansible coil spring 16 encircles the inner end portion of the driven shaft 3 and is disposed between the inner end of the spiral gear 15 and the bushing 6 as is clearly shown in the drawing. The portion of the shaft 3 which the coil spring 16 encircles is of such diameter as to be free to move longitudinally through the bushing 6, the shoulder 17 formed by the reduced portion 7 being adapted to engage the thrust bearing 18 disposed within the bushing 6 for limiting the inward sliding movement of the driven shaft 3 as will be presently apparent.

The operation of my improved starting device may be briefly stated as follows— With the parts arranged as shown in the drawing, the driving gear or pinion 10 which is secured on the outer end of the driven shaft 3 is out of engagement with the gear teeth 13 formed in the peripheral edge of the fly wheel 14. The expansible coil spring 16 normally holds the axial movable driven shaft in its outermost position and the pinion 2 which is secured on the outer end of the drive shaft 1 is in engagement with the spiral gear 15 at all times.

When the starting motor is operated, the drive shaft 1 will rotate in the direction indicated by the arrow as will also the drive pinion or gear 2. The pinion 2 will in turn drive the spiral gear 15 which is fixedly associated with the driven shaft 3 so that a

lateral thrust is exerted on the driven shaft whereby the same will move inwardly. As the driven shaft 3 moves axially in an inward direction, the coil spring 16 will be compressed and the gear or pinion 10 will be brought into engagement with the gear teeth 13 of the fly wheel 14 thus providing a cooperation between the starting motor (not shown) and the fly wheel for starting the internal combustion engine. As soon as the motor starts, the parts rotate and move in the reverse direction causing the pinion 10 to be disengaged from the gear teeth 13 and also, the coil spring 16 will return the axially movable driven shaft 3 to its initial position shown in the drawing.

It will thus be seen from the foregoing description that a starting device for internal combustion engines has been provided which is very simple in construction and operation and which will furthermore at all times be positive and efficient in carrying out the purposes for which it is designed.

The drive gear may be positioned at right angles to the driven shaft if so desired.

While I have shown the preferred embodiment of my invention it is to be understood that minor changes may be made in the invention without departing from the spirit of the invention and the scope of the appended claim.

Having thus described the invention, what I claim is:—

In an engine starting device of the class

described, a support including spaced side walls provided with registering openings, bushings arranged in the respective openings, a driven shaft journaled at its end portions in said bushings, said driven shaft being adapted for axial movement, the inner end of the driven shaft being reduced, a cover plate secured on the outer face of the inner side wall of said support over the opening therein, said cover plate being provided with an opening through which the reduced inner end of the driven shaft extends, a gear mounted on the outer end of the driven shaft and adapted to engage a member of the engine to be started, a drive shaft arranged in parallel spaced relation with respect to the driven shaft, a driving pinion secured on the outer end of said drive shaft, a relatively wide spiral gear keyed on the driven shaft at the intermediate portion thereof, said spiral gear cooperating with the driving pinion on the drive shaft to effect the axial movement of the driven shaft whereby the gear mounted on the outer end of the driven shaft is moved into operative engagement with said aforementioned member, and a normally expandable coil spring encircling the driven shaft and disposed between the inner end of the wide spiral gear keyed on the driven shaft, and the inner bushing for returning the driven shaft to its initial position.

In testimony whereof I affix my signature.

ULYSSES S. GEIGER.
